UNITED STATES PATENT OFFICE.

SOLON PALMER, OF NEW YORK, N. Y.

DESIGN FOR A CAKE OF SOAP.

SPECIFICATION forming part of Design No. 16,960, dated October 26, 1886.

Application filed September 14, 1886. Serial No. 213,538. Term of patent 14 years.

To all whom it may concern:

Be it known that I, SOLON PALMER, of the city, county, and State of New York, have invented and produced a new and original Design for a Cake of Soap, of which the following is a specification.

Reference is to be had to the accompanying drawings, forming a part of this specification, in which similar letters of reference indicate corresponding parts in both figures.

Figure 1 is a plan view of my newly-designed cake of soap, and Fig. 2 is a sectional view of the same.

The leading feature of my design consists of opposite curves bordering an ellipse that constitutes the center of the cake.

Another leading feature of the design is a shield represented at the center of the cake.

a represents the center of the cake, which is flat and elliptical in form. In the center of the ellipse appears the shield *b*, showing diagonal straight parallel edges *b' b'* and outwardly curved end edges, *b² b²*. Surrounding the elliptical center *a* are the opposite grooves *c*, the ends of which meet and form the points *c' c'*. Outside of the grooves *c* appear the oppositely-curved grooves or concaves *d d*, the ends of which are rounded, as shown at *d' d'*, and separated by flat surfaces *d² d²*. At the corners of the cake are formed

the raised triangular surfaces *e e*, which are surrounded by the grooves *e' e'*, the grooves *e'* each being a right-angled groove with a rounded corner, while the grooves *e'* are each made in the form of a curve concentric with the grooves *d* and meeting the ends of the groove *e'*. The edges of the cake are beveled, as shown at *f*.

I claim—

1. In a design for a cake of soap, the flat elliptical center *a*, combined with the oppositely-curved grooves *d*, depressed below the elliptical center, and shown upon the opposite sides of said center, substantially as shown in the accompanying drawings. 45

2. In a design for a cake of soap, the elliptical center *a*, the curved grooves *d*, depressed below the elliptical center, and the shield *b*, shown upon the elliptical center, substantially as shown in the accompanying drawings. 50

3. The design for a cake of soap herein shown and described, the same consisting of the elliptical center *a*, oppositely-curved grooves *d*, grooves *c*, and corner-grooves *e' e'*, 55 and the flat triangular surface *e*.

SOLON PALMER.
